CONTAINER FOR CIGARETTE PACKAGE
AND MATCH BOOK

Edward S. Caldwell, Chicago, Ill.

Application January 17, 1950, Serial No. 139,066

7 Claims. (Cl. 206—38)

1

My invention relates to containers which are adapted to hold a package of cigarettes, such as the conventional or standard packages, and which also serve to hold the usual paper packets of matches or books of matches as they are frequently called.

While containers for holding packages of cigarettes, with or without packages of matches, have heretofore been devised, all of them, so far as I am aware, have been characterized by one or more disadvantages as, for example, undesirability of appearance, relatively high cost of manufacture, and the like. In accordance with my invention, a container for cigarettes, particularly cigarettes and matches, has been evolved which provides not only a highly attractive appearance but, in addition, is of such simplicity in design that it may be manufactured in large volume and at very low cost. This enables it not only to be sold to the user for a minimum price but, also, it makes readily feasible the distribution thereof as advertising media gratis to the user. The container may be embellished in any desired manner and may have printed thereon the name of the proprietor of any establishment as, for example, a restaurant. Being low in cost, as pointed out above, said containers may be distributed gratis by such restaurant to its customers or prospective customers. Whenever a cigarette is removed from its package within the container, the user will have his attention directed to the name of the restaurant. This is illustrative of one manner of distribution of the container forming the basis for my present invention and it will be apparent that many other ways will suggest themselves to those versed in the art in the light of the low costs involved in the manufacture of such containers.

In my prior co-pending application, Serial No. 39,248, filed July 17, 1948, I have disclosed combination cigarette-match book containers which possess certain marked advantages over previously known containers used for such purposes. My present invention is distinguished from that disclosed in my aforesaid prior patent application and represents important advantages thereover. These advantages include the fact that my present containers present a distinctly better appearance and retain their shape and fullness during shipment and handling, when empty, much more satisfactorily than do the containers made pursuant to my aforesaid prior invention. It is easier to print desired indicia on said containers and a wider, unbroken area for such printing is provided. Moreover, in two-color or

2

multi-color containers, such colors show up much better and the over-all appearance of the containers is distinctly superior. Still other advantages exist which will be clear to those versed in the art without further elaboration.

The invention will be readily understood in the light of the accompanying drawing and the following description in conjunction therewith wherein a preferred embodiment of my invention is set out in detail.

Fig. 1 is a perspective view of a container made in accordance with my invention showing the manner of supporting a match book therein, said container being shown in closed position.

Fig. 2 is a perspective view which is similar to Fig. 1 except that the closure flap is shown in open position, the package of cigarettes within said container being exposed to view.

Fig. 3 is a vertical section taken along line 10 3—3 of Fig. 1, looking in the direction of the arrows.

Fig. 4 is a horizontal section taken along line 4—4 of Fig. 1, looking in the direction of the arrows.

Fig. 5 is a perspective view showing the container in incompletely assembled form but generally showing the manner in which the two blanks forming said container are assembled.

Figs. 6 and 7 are the two blanks from which the container is assembled.

As shown in the drawings, the container is made from two blanks A and B, shown, respectively, in Figs. 6 and 7, made from a flexible thermoplastic material such as a vinyl resin, a cellulose acetate resin or any other flexible thermoplastic sheet material. The blank A comprises an intermediate rectangular portion 10. Extending from one end of said portion 10 is a flap member 11 which, when in fully assembled condition, provides the bottom of the container and also provides the bottom of the pocket for housing the match book. The free end 12 of said flap member 11 is preferably arcuate-shaped and is provided with an aperture 13 through which is passed the male portion 14 of a standard snap closure.

Extending from the other end of said portion 10 is a cover-forming flap 15 which provides the top of the cigarette package and also the closure flap. The free end 16 of said flap member 15 is preferably arcuate-shaped and is provided with an aperture 17 through which passes the female portion 18 of the snap closure.

The member 11 is advantageously longer than 55 the member 10 and the latter, in turn, is longer

than the member 15. For the standard size package containing twenty cigarettes, I find it quite satisfactory for the member 11 to be about 3 $\frac{1}{16}$ inches in length, the member 10 to be about 2 $\frac{7}{8}$ inches in length, and the member 15 to be about 1 $\frac{3}{4}$ inches in length. As to width, it will be noted that the member 10 is slightly wider than the member 11. If desired, the member 15 may be of the same width as the member 11 and, less advantageously, the entire blank A may be of uniform width. Where the members 11 and 15 are made of the same width and narrower than the width of member 10, said members 11 and 15 are conveniently about 2 $\frac{1}{4}$ inches wide and the member 10 somewhat wider, for example, about 2 $\frac{7}{16}$ inches in width. The extra width in the member 10 serves to provide side extensions 19 and 21 for the purpose described hereafter.

The blank B, which comprises the cigarette package-forming pocket member, is made up of a generally rectangular sheet but one side 22 is preferably double-arcuate in shape having a centrally disposed depressed portion 23 and below which is disposed an aperture 24 through which the male portion 14 of the snap closure passes. The side opposite the side 22 is advantageously scalloped as shown. The length of said blank B corresponds generally to the height of the cigarette package and the width of said blank B is sufficiently greater than the width of member 10 so that, in assembled form, a pocket is provided of a size snugly to house the cigarette package. The width of blank B is conveniently about 4 $\frac{1}{8}$ inches.

The assembly of the blanks A and B is simple and rapid. The blank B is fitted over the blank A and held in position with the opposite edges of said blank B disposed along and in contact with the side extensions 19 and 21, respectively, of the blank A. The edges to be sealed are then disposed between the electrodes of an electronic sealing unit and the passage of current through said electrodes serves to melt the inner surfaces of the thermoplastic material and to effect sealing or "welding" to form seams 26 and 27 which are exceedingly strong and resistant to tear. The outer surfaces, which face the electrodes, are not marred in the sealing process. The flap member 11 is then folded upwardly under or beneath and generally in contact with the inner surface of blank B until the apertures 13 and 24 are aligned and the male portion 14 of the snap fastener is passed through said apertures. The female portion 18 of said snap fastener is then mounted through said aperture 17. It will be understood, of course, that the female portion 18 of said snap fastener may first be attached to the flap 15 and the flap 11 folded under and assembled as described above.

It will be seen, therefore, that, after the container is assembled, a cigarette package 28 may be placed in the pocket formed by members 10 and 11 and blank B and a packet of matches 29 may be inserted through the bottom opening into the space formed between the inner surface of blank B and the outer surface of member 11. When the cover flap 15 is closed, a neat, compact package results. It may be pointed out that the curvature of the side 22 is such that it abuts firmly against the cover flap 15 when the latter is in closed position so as to form a relatively tight closure to prevent leakage of loose tobacco.

Containers made in accordance with my invention also have the advantage of protecting

the contents thereof from perspiration. They possess a very slight adhesion to cloth and, therefore, they do not have the tendency to fall out of the pocket of a workman's shirt or the like despite frequent bending or stooping. They are light in weight and, being flexible, they have a long life and may be carried without discomfort in one's pocket. Other advantages will readily appear to those versed in the art in the light of my disclosure herein.

While I have described my invention in detail, it will be understood that no unnecessary limitations are to be read thereinto, the scope of the invention being pointed out in the appended claims.

What I claim as new and desire to protect by Letters Patent of the United States is:

1. A container which is adapted to hold a package of cigarettes and a book of matches, said container being formed from two blank members made of flexible thermoplastic sheet material, the first of said blank members comprising a generally rectangular portion, a flap extending from one end of said rectangular portion and a cigarette package cover-forming flap extending from the other end of said rectangular portion, the second of said blank members having a width substantially exceeding the width of the rectangular portion of said first blank member, said second blank member being heat-sealed at its opposed longitudinal edges to the edges of said rectangular portion of the first blank member to provide a cigarette package receiving pocket, said first-mentioned flap being folded under and in contact with the inner surface of said second blank member to form the bottom of said pocket and being connected near its free end to said second blank by one part of a snap fastener, a match pocket being formed between the inner surface of said second blank member and the outer surface of said first-mentioned flap and being open at its bottom for the reception of a match book, and the other part of said snap fastener being attached to the cigarette package cover-forming flap.

2. A container which is adapted to hold a package of cigarettes and a book of matches, said container being formed from two blank members made of flexible thermoplastic sheet material, the first of said blank members comprising a generally rectangular portion, a flap extending from one end of said rectangular portion and a cigarette package cover-forming flap extending from the other end of said rectangular portion, said flaps being of substantially equal width and said rectangular portion being slightly wider than said flaps so as to provide side extensions on said rectangular portion, said rectangular portion being greater in length than said cigarette cover-forming flap and lesser in length than said first-mentioned flap, the second of said blank members being generally rectangular with the exception of at least one side which is double-arcuate in shape and has a centrally depressed portion, said second blank member having a width substantially exceeding the width of the rectangular portion of said first blank member, said second blank member having a length approximately equal to the length of said side extensions and being heat-sealed at its opposed longitudinal edges to said side extensions to provide a cigarette package receiving pocket, said first-mentioned flap being folded under and in contact with the inner surface of said second blank member to form the bottom of said pocket and being connected near

its free end to said second blank by one part of a snap fastener, a match pocket being formed between the inner surface of said second blank member and the outer surface of said first-mentioned flap and being open at its bottom for the reception of a match book, and the other part of said snap fastener being attached to the cigarette package cover-forming flap.

3. A container which is adapted to hold a package of cigarettes and a book of matches, said container being formed from two blank members made of flexible thermoplastic sheet material, the first of said blank members comprising a generally rectangular portion, a flap extending from one end of said rectangular portion and a cigarette package cover-forming flap extending from the other end of said rectangular portion, said flaps being of substantially equal width and said rectangular portion being slightly wider than said flaps so as to provide side extensions on said rectangular portion, said rectangular portion being greater in length than cigarette cover-forming flap and lesser in length than said first-mentioned flap, the second of said blank members having a width substantially exceeding the width of the rectangular portion of said first blank member, said second blank member having a length approximately equal to the length of said side extensions and being heat-sealed at its opposed longitudinal edges to said side extensions to provide a cigarette package receiving pocket, said first-mentioned flap being folded under and in contact with the inner surface of said second blank member to form the bottom of said pocket and being connected near its free end to said second blank by one part of a two-part fastener, a match pocket being formed between the inner surface of said second blank member and the outer surface of said first-mentioned flap and being open at its bottom for the reception of a match book, and the other and cooperating part of said fastener being attached to the cigarette package cover-forming flap.

4. A container which is adapted to hold a package of cigarettes, said container being formed from two blank members made of flexible thermoplastic sheet material, the first of said blank members comprising a generally rectangular portion, a first flap extending from one end of said rectangular portion and a second flap extending from the other end of said rectangular portion, the second of said blank members having a width substantially exceeding the width of the rectangular portion of said first blank member, said second blank member being heat-sealed at its opposed longitudinal edges to the edges of said rectangular portion of said first blank member to provide a cigarette package receiving pocket, said first flap being folded under and in contact with the inner surface of said second blank member to form the bottom of said pocket and being connected near its free end to said second blank by one part of a snap fastener, a match pocket being formed between the inner surface of said second blank member and the outer surface of said first flap and being open at its bottom for the reception of a match book, and the other part of said snap fastener being attached to said second flap.

5. A container which is adapted to hold a package of cigarettes, said container being formed from two blank members made of flexible thermoplastic sheet material, the first of said blank members comprising a generally rectangular portion, a first flap extending from one end of said

rectangular portion and a second flap extending from the other end of said rectangular portion, said flaps being of generally similar width, the second of said blank members having a width substantially exceeding the width of the rectangular portion of said first blank member, said second blank member being heat-sealed at its opposed longitudinal edges to the side edges of said rectangular portion of said first blank member to provide a cigarette package receiving pocket, said first flap being folded under and in contact with the inner surface of said second blank member to form the bottom of said pocket and being connected near its free end to said second blank by one part of a snap fastener, a match pocket being formed between the inner surface of said second blank member and the outer surface of said first flap and being open at its bottom for the reception of a match book, and the other part of said snap fastener being attached to said second flap.

6. A container which is adapted to hold a package of cigarettes and a book of matches, said container being formed from two blank members made of flexible thermoplastic sheet material, the first of said blank members comprising a four-sided portion, a first flap extending from one end of said four-sided portion and a second flap extending from the other end of said four-sided portion, the second of said blank members having a width substantially exceeding the width of the widest part of said four-sided portion of said first blank member, said second blank member being heat-sealed at its opposed longitudinal edges to said four-sided portion to provide a cigarette package receiving pocket, said first flap being folded under and in contact with the inner surface of said second blank member to form the bottom of said pocket and being connected near its free end to said second blank by one part of a two-part snap fastener, a match pocket being formed between the inner surface of said second blank member and the outer surface of said first flap and being open at its bottom for the reception of a match book, and the other and cooperating part of said snap fastener being attached to said second flap.

7. A container which is adapted to hold a package of cigarettes and a book of matches, said container being formed from two blank members made of flexible thermoplastic sheet material, the first of said blank members comprising a four-sided portion, a flap extending from one end of said four-sided portion and a cigarette package cover-forming flap extending from the other end of said four-sided portion, said four-sided portion at its widest dimension having a width not less than the width of either of said flaps so as to provide extensions at two opposing sides on said four-sided portion, the second of said blank members having a width substantially exceeding the greatest width of the four-sided portion of said first blank member, said second blank member being heat-sealed at its opposed longitudinal edges to said side extensions to provide a cigarette package receiving pocket, said first-mentioned flap being folded under and in contact with the inner surface of said second blank member to form the bottom of said pocket and being connected near its free end to said second blank by one part of a snap fastener, a match pocket being formed between the inner surface of said second blank member and the outer surface of said first-mentioned flap and being open at its bottom for the reception of a

match book, and the other part of said snap fastener being attached to the cigarette package cover-forming flap.
